UNITED STATES PATENT OFFICE

LEO E. WATTS, OF ENID, OKLAHOMA, ASSIGNOR TO JOHN F. HOLTZEN, OF ENID,
OKLAHOMA

IRONING BOARD

Application filed September 4, 1929. Serial No. 390,302.

The present invention relates to ironing boards and more particularly to an ironing board installation affording improvements over the Letters Patent No. 1,619,774 issued 5 to me on March 1, 1927, and the general object of my present improved structure resides in the provision of an ironing board installation in which the board means may be expeditiously adjusted for use at any 10 desired height and is easy to fold and unfold in respect to its casing.

A further very important object of the invention resides in the provision of an ironing board installment of this nature which 15 is exceedingly simple in construction, inexpensive to manufacture and install, thoroughly efficient and reliable in use, and otherwise well adapted to the purpose for which it is designed.

With the above and numerous other objects in view as will appear as the description proceeds, the invention resides in certain novel features of construction, and in the combination and arrangement of parts as 25 will be hereinafter more fully described and claimed.

In the drawing:

Figure 1 is a front elevation illustrating my improvement with the door of the casing 30 open and the ironing board and its appurtenances compactly stored in said casing.

Figure 2 is a sectional view taken substantially on the line 2—2 of Figure 1 but showing the ironing board and sleeve board 35 extended,

Figure 3 is a detail vertical sectional view illustrating particularly the height adjusting means,

Figure 4 is a similar view showing the 40 plate thereover,

Figure 5 is a sectional view taken substantially on the line 5—5 of Figure 4, and

Figure 6 is a plan view of the inner end of the sleeve board.

Referring to the drawings in detail it

will be seen that a casing 1 is preferably, though not necessarily, housed in a wall. The casing 1 is closed by a door 3, the said door being preferably of hinged type. The inner faces of the side walls are provided with vertically extending channels or grooves 4 which slidably receive ends of bars 5 and 6 and reduced ends 7 of bar 8.

A stop shelf 9 is provided across the lower portion of the casing. A prop 10 is hingedly connected as at 11 with the bar 8. A main ironing board 12 is formed at the inner end of its side edges with lateral lugs 14 slidable in the channels 4. A cleat 15 extends under and across an intermediate portion of the 60 main board 12 and the prop 10 is hingedly engaged therewith as at 16.

An abutment cleat 17 is fixed across the top surface of the inner end of the main board 12. Vertical strips 18 are connected to the 65 bars 5, 6 and 8 holding them in predetermined spaced parallel relationship in respect to each other.

The inner edges of these strips 18 are channeled as is indicated at 19. A sleeve board 70 20 is provided at its inner end with laterally extending lugs 21 movable in the channels 19. A stop cleat 22 is disposed across the upper ends of the strips 18 while the channels 19 terminate a distance from the lower ends 75 thereof so that the sleeve board 20 may be disposed in the position shown in Figure 4 with its lugs 21 resting in the bottom end of the channel or may be moved to the position shown in Figure 2 resting on the bar 5 80 and bearing upwardly against the stop cleat 22.

A bar 24 is slidably mounted between the bars 5 and 6 and have one end disposed in one of the channels 4 while the other end is notched as is indicated at 25. A rod 26 has one end seated in the crotch of the notch 25 and the other end extending into the other channel 4 and said latter end is urged upwardly 85 by means of a spring 27 attached to the rod 90

26 intermediate its ends and to the bar 24 adjacent the upper edge of the notch 25 for normally binding the bar 25 and the rod 26 into the channels 4 so that the apparatus may be held at any desired adjusted height.

A plate 30 is fixed on the bars 5 and 6 to house the bar 24 and the rod 26 but is provided with a notch 31 so that access may be had to the rod 26 to push the same downwardly thereby releasing the binding action when adjustments are desired.

It is thought that the construction, operation, utility and advantages of this invention will now be quite apparent to those skilled in this art without a more detailed description thereof.

The present embodiment of the invention has been described in considerable detail merely for the purposes of exemplification, 20 since in actual practice it attains the features of advantage enumerated as desirable in the statement of the invention and the above description.

It will be apparent that changes in the design
25 tails of construction, and in the combination
and arrangement of parts may be resorted to
without departing from the spirit or scope
of the invention as hereinafter claimed or
sacrificing any of its advantages.

30 Having thus described my invention, what I claim as new is:

1. A means for the purpose described, the combination of a casing having vertical runways on the inner sides of opposed walls thereof, a body disposed and movable in said runways, a bar slideable in said body into one of said runways and having a notch at the other end thereof, a rod extending into the notch and into the other runway, and a spring urging said rod in one direction to bind the bar and rod in the runway to hold the body in adjusted position, and a board operatively connected with said body.

2. A means for the purpose described, the combination of a casing having vertical runways on the inner sides of opposite walls thereof, a pair of bars disposed in spaced parallelism with respect to each other and having ends slideable in the runways, a third bar slideable between the first mentioned bars to have one end disposed in one of the runways and the other end formed with a notch, a rod extending into the notch and into the other runway, a spring connected with said rod to urge it in a direction to cause binding action of the third mentioned bar and the rod with respect to the runways to hold the first mentioned bars in adjusted position an ironing board, and means operatively connecting the ironing board with the first mentioned bars.

3. A means for the purpose described, the combination of a casing having vertical runways on the inner sides of opposite walls thereof, a pair of bars disposed in spaced par-

allelism with respect to each other and having ends slideable in the runways, a third bar slideable between the first mentioned bars to have one end disposed in one of the runways and the other end formed with a notch, a rod extending into the notch and into the other runway, a spring connected with said rod to urge it in a direction to cause binding action of the third mentioned bar and the rod with respect to the runways to hold the first mentioned bars in adjusted position, an ironing board, a pair of strips fixed to the pair of bars first mentioned and depending downwardly therefrom, a bar across the lower end of the strips having reduced ends extending into the runway, a brace hingedly connected with the last mentioned bar and hingedly connected with an intermediate portion of the ironing board, said ironing board having lugs extending into the runways at its inner ends.

4. A means for the purpose described, the combination with a sleeve board and an ironing board; a casing having vertical runways on the inner sides of opposite walls thereof, a pair of bars disposed in spaced parallelism with respect to each other and having ends 90 slidable in the runways, a third bar slidible between the first mentioned bars to have one end disposed in one of the runways and the other end formed with a notch, a rod extending into the notch and into the other runway, a spring connected with said rod to urge it in a direction to cause binding action 95 of the third mentioned bar and the rod with respect to the runways to hold the first mentioned bars in adjusted position, a pair of strips fixed to the pair of bars first mentioned and depending downwardly therefrom, a bar across the lower end of the strips having reduced ends extending into the runway, a brace hingedly connected with the last mentioned bar and hingedly connected with an intermediate portion of the ironing board, 100 said ironing board having lugs extending into the runways at its inner ends, the inner edges of said strips being channeled, said sleeve board having lugs movable in the channels. 105 110

5. A means for the purpose described, the combination with a sleeve board and an ironing board, a casing having vertical runways 115 on the inner sides of opposite walls thereof, a pair of bars disposed in spaced parallelism with respect to each other and having ends 120 slideable in the runways, a third bar slideable between the first mentioned bars to have one end disposed in one of the runways and the other end formed with a notch, a rod extending into the notch and into the other runway, a spring connected with said rod to urge it 125 in a direction to cause binding action of the third mentioned bar and the rod with respect to the runways to hold the first mentioned bars in adjusted position, a pair of strips fixed to the pair of bars first mentioned and depending downwardly therefrom, a bar 130

across the lower end of the strips having reduced ends extending into the runway, a brace hingedly connected with the last mentioned bar and hingedly connected with an intermediate portion of the ironing board, said ironing board having lugs extending into the runways at its inner ends, the inner edges of said strips being channeled, said sleeve board having lugs movable in the channels; a 10 stop cleat across the upper ends of the strips so that the sleeve board when extended may rest on the uppermost bar and press upwardly against the cleat.

In testimony whereof I affix my signature.

LEO E. WATTS.
